BOOK INDEXING MACHINE

Hjalmar Erickson, Cambridge, Mass.

Application August 14, 1936, Serial No. 96,035

15 Claims. (Cl. 164—48)

This invention relates to book-indexing machines, of the type used to cut index notches in the sides of pages of books, particularly dictionaries and reference books, to indicate where the indexed subject matter is to be found.

While book indexing machines are not unknown, previous machines have either been impractical or are not sold today. So far as I am aware, indexing is done commercially today by a hand punch, and the operation usually requires three operators, two, separately to find the page in the book where the indexed subject matter begins and place a marker therein, and another to operate the hand punch on the page marked. The hand punch operator can work as fast as two page finders. By means of my machine I am able to eliminate two operators entirely, as the machine operator both finds the page of the book and operates the machine. This results in a great saving of time, as it is as easy for the operator to step on the treadle and cut the notch in the page marked as to insert a marker. In this manner I also eliminate separate handling of the books by the operators. By means of my machine using one operator, I am enabled to complete the indexing operation in, at least, half the time formerly taken and at half the expense.

My machine, briefly, comprises a frame, a work support for holding the open book whose pages are to be notched, a cutting tool, means providing relative movement between the work support and the cutting tool to bring them into and out of operating position, means to operate the cutting tool, means providing a gradual advance of the cutting tool into and up the side of the open book as its pages recede, means providing step-by-step movement between the cutting tool and the book across the length of the book, and an electric motor or other source of energy for operating the machine.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

Fig. 1 is a side elevation of the machine as seen from the left side of the operator.

Fig. 2 is a rear elevation of the same.

Fig. 3 is a top plan view.

Figs. 4 and 5 are diagrammatic views showing the way in which the edges of the book leaves are cut by the cutting tool.

Fig. 6 is a side view similar to Fig. 1, partly broken away, showing the mechanism to slide the work table to and from the path of the cutting tool.

Fig. 7 is a side view illustrating the mechanism to operate the cutting tool.

Fig. 8 is a fragmentary view of the cutting tool on a larger scale.

Fig. 9 is an enlarged rear view similar to Fig. 2 showing the mechanism to move the tool support carriage.

Figs. 10, 11, 12 and 13 are fragmentary views illustrating the feeding and releasing operation of the carriage.

Fig. 14 is a vertical cross section of the carriage, partly broken away.

Fig. 15 is a fragmentary view of part of the carriage mechanism.

Fig. 16 is a rear view and Fig. 17 a side elevation from the left of a modification of my machine in which the work table is stationary and the cutting tool is moved to and from said table.

In the accompanying drawings, 10 represents a table having two pairs of legs 11 and 12 which are reinforced by cross frame members 13 and 14 and a rear longitudinal member 15 in order to form a rigid frame or unit. A second pair of cross members 16 and 16a are placed between each pair of legs 11—11 and 12—12, said cross member being secured by means of bolts or screws 17 to brackets 18—18 forming part or being rigidly attached to legs 11 and 12 as shown at 19.

A table or bed plate 20 acts as a work support and is slidably mounted between side members 21 and 22 provided with guide ways 21a and 22a in which plate 20 slides to and fro to bring the work in and out of punching or operating position, as will be hereinafter more fully described. Side members 21 and 22 are rigidly mounted on posts 23 which form part or are fast on table 10 and hold side members 21 and 22 in an inclined position with respect to table 10 as is clearly seen in Figs. 1 and 3. Adjustable U-shaped positioning clamps 8—8 and 9—9 are provided on bed plate 20 to hold the work at the front and rear of the plate, and pins 7—7 serve to keep the work in alignment and in proper position for presentation to the cutting tool.

Side members 21 and 22 have rearwardly extending portions 24 and 25. Portion 24 supports

- one end of slide bar 26 rectangular in section on which a tool carriage, generally shown at 27, is adapted to slide, said bar 26 being secured to portion 24 by means of screws 28 (see Fig. 3). 5 Portion 24 terminates in a bearing 29 intended to receive one end of a slide rod 30 on which a slide bearing 31 forming part of carriage 27 travels. Extending portion 25 of side member 22 likewise supports the opposite end of slide bar 26 10 which is secured to portion 25 by means of bolts and nuts 26a and the other end of slide rod 30 is journalled in a bearing 32 forming part of a bracket 33 rigidly secured to table 10 by means of bolts and nuts 34.
- 15 Mounted in any convenient way on cross member 16a is a double bearing 35 on which a short shaft 36 is journalled. One end of this shaft has keyed on it a pulley 37 driven from a source of power, not shown, through a belt 38. The 20 opposite end of shaft 36 has also keyed on it a pinion 39 adapted to mesh with a gear 40 forming part of one element 40a of a one-revolution clutch mechanism generally shown at 41 and mounted on a cam and main drive shaft 42. This shaft 25 extends from one side to the other side of the frame under table 10 and is rotatably connected at one end to double bearing 35 and at the other end to a single bearing 43 secured to or forming part of cross member 16 of the frame.
- 30 The clutch mechanism is as follows: A second clutch element 44 (see Fig. 2) forms part or is rigidly secured to a cam 45 on shaft 42 and adapted to rotate with it. A ring 46 between clutch elements 40a and 44 has a groove 46a in which a key 47 slides. This key slides and projects also in a pocket 48 provided in clutch element 44, and a spring 49 in said pocket constantly forces key 47 towards engagement with a notch 50 cut out on clutch element 40a. A wedge shaped member 51 designed to throw the clutch in and out of 40 operation is secured to a rod 52 slidably mounted in a bearing 53 forming part of a bracket 54 rigidly attached to cross member 16a as by bolts 55, said rod being connected to a foot treadle 56 by means of a link 57. Foot treadle 56 is pivoted to a member 58 forming part of the frame. A spring 59 attached at one end to rod 52 and at the other to bracket 54 is normally forcing rod 52 and wedge shape member 51 against a cam shaped face 47a of key 47 in a manner as to 45 force the key against the pressure of spring 49 and keep it out of engagement with notch 50 of clutch element 40a. Thus it will be seen that if key 47 is out of engagement with notch 50, gear 49 will rotate idly when driven by pinion 39. But 50 if foot treadle 56 is stepped on and wedge member 51 releases key 47, this will lock both elements of the clutch and shaft 42, together with the different cams attached to it, will rotate as a unit with gear 40.
- 55 In the present instance there are three cams 45, 60 and 61 carried by main drive shaft 42. Cam 45, which is pear-shaped, serves to move the different parts of the mechanism operating the cutting tool. Cam 60 serves to operate the 60 mechanism providing step-by-step movement of the tool carriage 27, and cam 61 operates the mechanism moving the bed plate 20 into and out of punching position.
- 65 The mechanism acting on bed plate 20 and carrying the work to and from the path of the cutting tool, and thus into and out of operative position is better illustrated in Figs. 1 and 6. This mechanism comprises a foot treadle 62 which, like clutch treadle 56, is also pivoted to

member 58 of the frame. A vertical rod 63 is pivoted to treadle 62 as shown at 64, and its upper end is journalled in a socket 65 secured to table 10 in any convenient way. A spring 66 around the rod and inside a chamber 67 formed in socket 65 engages a laterally extending pin 68 rigidly secured to rod 63 and constantly forces the rod in an upward direction, but this movement is limited by the end of a slot 69 in which pin 68 slides. The upper end of rod 63 terminates in flat inclined edge 63a which is adapted to engage a tooth 70 fast to the underside of bed plate 20. Thus it will be seen that if bed plate 20 is shifted to the right in Fig. 1 (toward the operator and away from the cutting tool) tooth 70 will force rod 63 down against the pressure of spring 66, but once the tooth has passed over the rod, it will snap back to its original position and prevent the table from moving back again toward the cutting tool and to operating position.

70 A bracket 71 riveted to the underside of plate 20, slidably receives one end of a rod 72 which passes through a hole 71a in the bracket, the other end of this rod being suitably mounted 25 on a cross member 73 secured between posts 23 supporting side members 21 and 22. (See particularly Figs. 3 and 6.) A coil spring 74 surrounds rod 72 and one of its ends engages bracket 71 while the other end rests against cross member 73. It will be clearly seen that by means of this construction plate 20 is constantly urged to move in a direction toward the path of a punching mechanism and cutting tool generally shown at 75. A bell-crank lever 76 carrying a friction roll 76' is pivotally mounted to a shaft 77 supported by two bearings 78-78 secured to the side ends of table 10, and has an extending arm 79 designed to engage and disengage another friction roll 80 rotating on a bracket 81 secured to 30 the underside of plate 20. Roll 76' is in constant engagement with cam 61, consequently each time cam 61 completes one revolution, arm 79 moves to engage roll 80 and force plate 20 to slide away from the path of punching mechanism 75. Thus 35 it will be seen that by means of this arrangement, feeding of the work to and from the path of the punching mechanism is obtained and that this feeding is controlled by the operator through foot treadle 62. In other words, every time the operator desires to have the work brought in punching position he simply steps on the treadle 62 thus forcing rod 63 to move down and disengage tooth 70. This sets plate 20 free to move into punching position by the force of spring 74 which 40 will hold the plate and consequently the work in said position until cam 61 rotates again, forcing arm 79 of lever 76 to act against roll 80 and move plate 20 to its original position. In Fig. 6 I show in full lines work plate 20 and the different parts of the feeding mechanism in punching position while the dotted lines indicate the parts as they move to shift bed plate 20 from the path of punching mechanism 75.

45 Punching mechanism 75 and its operating means is as follows:

50 Tool carriage 27 includes a block 82 provided with side walls 83 and 84 forming grooves 85 and 86 and is adapted to slide on slide bar 26 when fed step-by-step along said slide by a mechanism 70 which will be more fully described later. This block or carriage 82 includes an upwardly extending sleeve 87 ending in a bearing 88 and is adapted to slidably receive a tool carrying rod 89 having on one side a toothed or rack portion 75

90 and on the other a laterally extending tool carrying arm or bracket 91 projecting through a vertical slot 92 cut in said sleeve.

Adjustably secured to the end of arm 91 is a cutting tool 93 of special design which is more clearly shown in Fig. 8. This tool comprises a threaded stem 94 and a cutting portion 95 tubular in section, having sharp edges 95a adapted to sever the work, the pages of a book in this instance, and produce on this a cut-out portion or notch semi-circular in shape. Nuts 96 and 97 serve to adjustably secure stem 94 to arm 91.

The inside of tool 93 forms a chamber 98 having an opening 99 which registers with a conduit 100 forming part of a fitting 101 secured to the outside of portion 95 of the tool by a set screw 102, and conduit 100 connects with a rubber or flexible tube 103 leading to a vacuum source not shown in the drawings. The object of this vacuum is to take away from the tool the paper fragments 104 cut from the book leaves, which otherwise would clog the tool and render it inoperative.

Rigidly clamped to sleeve 87 as by screws 105 is a ring 106 having on one side extensions 107 which terminate in a punching plate 108 adapted to receive the leaves of the book and against which the tool punches. This plate has a pad 109 of fiber or any other suitable material to protect the edges 95a of the tool. A second ring 110 is also clamped to sleeve 87 by screws 111 and has an extending arm 112 on which two vertical members 113, one at each side of bracket 91, are secured by screws 114, and serve as a guide for said bracket 91.

Housed inside of bearing 88 and pivoted to its side walls is a small shaft 115 to which is secured a pinion 116 adapted to mesh constantly with rack portion 90 of rod 98. A lever 117 is secured to one end of shaft 115 and said lever connects through a universal joint 118 with a second lever 119 which through another universal joint 120 connects with an arm 121 keyed to but allowed to slide on rod 30 between the two arms 31a of slide bearing 31 (see Figs. 2 and 3). A second arm 122 is rigidly secured to slide rod 30 near its engagement with bearing 32 and connects through a universal joint 123 a lever 124, which through another universal joint 125 connects a lever 126 pivoted to shaft 77. A friction roll 127 pivoted at 128 to lever 126 engages cam 45 and a spring 129 having one of its ends attached at 130 to lever 126 while its other end is secured to frame member 15, serves to keep roller 127 in constant engagement with pear-shaped cam 45.

From the description of this mechanism it will be seen that for each revolution of pear-shaped cam 45, lever 126 is moved in an upward direction and that said lever 126 through lever 124 forces arm 122 to rotate slide rod 30. This movement is transmitted by rod 30 and through arm 121 and levers 119 and 117 to pinion 116, which, being in engagement with tool carrying rod 89, will impart to this rod a downward movement, thus allowing the tool to perform the cutting operation on the work. Since all the parts of this mechanism move against the tension of spring 129 it is obvious that they are returned to their original position by said spring at the end of each cycle.

The mechanism providing a gradual advance of the cutting tool into and up the sides of the book as its pages recede will now be described.

Referring to Figs. 4 and 5 it will be noticed that the cut-out portions 131 are made at graduated distances, from the edge 132 of the open book

and that, in this instance, thirteen notches corresponding to half of the alphabet are made on one side of the book while the other thirteen corresponding to the other half of the alphabet are made on the opposite side of the book. This means that bed plate 20 supporting the book has to move toward the path of the cutting tool farther into and up the side of the book a different distance for each notch to be cut. In order to obtain this and to bring the book to its exact position each time, the following mechanism is employed. A bar 133 is mounted to rotate on two bearings 134 and 135 secured to the underside of bed plate 20, and said bar carries two series of stop pins 136 and 137 of different lengths; one series corresponds to the notches of one side of the book while the other series corresponds to the other side. A hand lever 138 rigidly secured to one end of bar 133 is adapted to rotate the bar one-fourth of a turn and thus change the series of pins when desired. A stop bracket 139 is adjustably secured to side 84 of carriage block 82 by means of screws 140 and is designed to engage each corresponding pin on bar 133 as the carriage advances step-by-step and the work is fed by bed plate 20 to have a notch cut out. In Fig. 6 I have illustrated the two positions of lever 138 as pin bar 133 is moved to change from one series of pins to the other.

The mechanism to move the tool carriage 27 step by step along the edge of the book or work is shown in Figs. 9 and 15. This mechanism is as follows:

Longitudinally located under slide bar 26 there are two racks 141 and 142 running parallel to each other. Rack 141 is rigidly secured to the bottom of slide 26 while rack 142 is adapted to have a reciprocating movement and is slidably held against the bottom of slide 26 by means of plates 148, 149 secured to slide 26 by screws 150. Both racks 141 and 142 are provided with ratchet teeth 143 and 144 respectively which are adapted to engage pawls 145, 146 pivoted on a pin 147 secured between side walls 83 and 84 of carriage block 82. A pair of leaf springs 150 and 151 anchored to a plate 152 secured to block 82 are adapted to engage pawls 145 and 146 respectively and keep said pawls in constant engagement with ratchet teeth 143 and 144 of racks 141 and 142. The purpose of these teeth will be described later.

The left end of rack 142, as is clearly shown in Fig. 9, is longer than that of rack 141 and has rigidly attached to it as by screws 153 a downwardly disposed arm 154 the end of which is pivotally connected at 155 to a horizontal lever 156. The opposite end of this lever is pivoted at 157 to an arm 158 forming part of a lever 159 fulcrumed at 160 on a bracket 161 secured to the underside of table 10. An opening 162 is provided in table 10 and through this opening arm 158 projects to connect with lever 156 as described. Lever 159 has a downwardly bent portion 163 pivotally carrying at its end a friction roll 164 which engages cam 60. One end of a coil spring 165 is secured at 166 to arm 154 while its other end is attached to a post 167 secured to table 10. Thus it will be seen that each rotation of cam 60 will move the several parts of this mechanism to the position shown in dotted lines in Fig. 9 and spring 165 will force them back to their original position, a distance determined by the configuration of cam 60, which corresponds with the pitch of ratchet teeth 143 and 144 on racks 141 and 142 and with the distance between the cen-

ter of stop pins 136 and 137 on bar 132 which, as said before, is equal to the distance between the centers of the notches cut out in the book. Secured at 169 to block 82 there is a chain or 5 cable 170 passing over a pulley 171 pivotally mounted at 172 to one of the posts 23 supporting bed plate 20. Cable 170 passes also over a second pulley 173 pivoted at 174 to cross member 23a of the bed plate supporting frame and has secured 10 to its end 175 a counterweight 176. This counterweight is constantly forcing carriage block 82 to move towards the left in Fig. 9.

In Fig. 10 I show a vertical longitudinal section of tool carriage block 82 and illustrate the manner in which said block is moved step by step toward the right of the figure. Face 168 of one of the teeth 144 of rack 142 is in engagement with pawl 146 thus forcing block 82 to slide on bar 26 against the action of counterweight 176. 15 Since rack 141 is rigidly secured to slide bar 26 and this bar is stationary, the movement of block 82 to the right of the figure, as shown by the arrows, will cause pawl 145 to drag on the inclined portion 177 of one of the teeth 143 against the pressure of leaf spring 150, which, as soon 20 as the pawl has passed the edge of said tooth, will force the pawl to snap back in the notch formed by the teeth and engage the vertical face 178 of the tooth, thus preventing the movement of block 82 towards the left of the figure. At this moment movable rack 142 starts to back thus forcing pawl 146 to drag on the inclined portion of the next corresponding tooth in the same manner pawl 145 did, until said pawl 146 reaches 25 the next notch and snaps back in locking position due to the pressure applied to it by leaf spring 151. As explained before this operation is repeated every time cam 60 turns one revolution, the tool carriage thus being moved step by step until it reaches the right end notches (as in Fig. 9) of racks 141 and 142, which coincide with the last perforation made on one half of the book. At this movement, the operator turns the book around to start the perforations of the other half of said book and for this purpose he first 30 moves lever 138 to change the position of bar 133 and bring the second series of stop pins 136 into play. But for this new operation it is necessary first to move tool carriage 27 back to its starting position. This is accomplished in the following 35 way, and is clearly shown in Figs. 11 to 15. Inwardly projecting pins 179 and 180 are secured to the inner walls of pawls 145 and 146 (see particularly Fig. 14) and are adapted to be engaged by an arm 181 rigidly secured to a shaft 183 journaled in side walls 83 and 84 of block 82. A second arm 184 secured to the end of shaft 183 by means of a set screw 185 carries at its extreme end a plunger 186 constantly urged by a spring 187 to frictionally engage depressions 188 and 189 40 formed on the face of wall 83 of block 82. An adjustable pin 190 is secured in any suitable way to one end of slide bar 26 while a second adjustable pin 191 (see Fig. 9) is secured to the other end of said bar, and these pins are designed to 45 engage respectively each side of arm 184, thus simultaneously moving pawls 145 and 146 in or out of engagement with the notches of their corresponding racks 141 and 142.

Right after tool carriage 27 has reached the 50 last notch, cam 60 will again move said carriage in the form described before, but as it does (see Figs. 11 and 12) arm 184 engages pin 190 which forces the arm back and through inner arm 181 which engages pins 179 and 180 simultaneously, 55 moves pawls 145 and 146 out of engagement with

the teeth, thus setting tool carriage 27 free to be moved to the opposite end by the action of counterweight 176.

When, as shown in Fig. 13, tool carriage 27 reaches its starting position, arm 184 engages pin 190 and moves it in the opposite direction, thus releasing pawls 145 and 146 which then are forced to engage again racks 141 and 142 by springs 152 and 151. The object of plunger 186 on arm 184 is to keep said arm locked in position until it is engaged by either of pins 190 and 191, thus preventing any accidental release of tool carriage 27.

An air cushion 192 of any known design, secured to the top of slide 26, is adapted to engage 15 block 82 of the carriage and serves to absorb the shock produced by the rapid movement of said carriage when brought to its starting position by counterweight 176.

In operation, the machine operator first places 20 the open book on bed plate 20 against gauge pins 7 taking care that both sides of the book cover are inserted and held in position by clamps 8-8 and 9-9. In this case, the number of leaves on one side of the book represent the first thirteen 25 letters of the alphabet while the leaves on the opposite side represent the other thirteen.

When power is applied to belt 38, pulley 37, pinion 39 and gear 40 will rotate idly and be ready to act on the different parts forming the mechanism. The operator selects the book leaves corresponding to the first letter of the alphabet to be punched out and holding them in his hands, steps on foot treadle 62 thus releasing bed plate 20 which slides towards the path of the cutting 30 tool and stops there. The operator then places the pack of leaves on plate 108 under cutting tool 95 as clearly shown in Fig. 1 and steps on clutch treadle 56 thus throwing the clutch in engagement and consequently allowing cam shaft 42 to 40 turn one revolution, at the end of which and as it has been explained before, clutch member 51 acts to disengage the clutch and move the corresponding parts into idling again.

During this single rotation of cam shaft 42, 45 cam 45 acts to operate the cutting tool first and then cams 60 and 61 act on their respective mechanisms; cam 60 to advance the carriage one step and cam 61 to shift bed plate 20 to its original position or away from the path of the cutting tool. This comprises one cycle of operation necessary for each notch cut out in the book and is repeated time after time until the thirteenth notch has been cut when the carriage returns to its starting position and the operator turns the book around to start the second series of notches 50 in the form already described.

While I have described the machine as operating on a dictionary having two rows of thirteen notches each, it is to be understood that the machine operates on other books requiring more or less index notches by substituting new racks 55 141 and 142 with the required number and spacing of teeth, and with a different inclination from left to right as in Fig. 2.

Figs. 16 and 17 show a modification of my machine in which the work table is stationary and cutting tool is moved to and from said table. Here the work support 20 is rigidly mounted on table 10 on posts 23. The entire cutting tool or 60 punching mechanism 75 is slidably mounted on two supports 200 adapted to slide in inclined slide-ways 202 provided at each end of table 10. Extending portions 200a rigidly secured to the under- 65 side of supports 200 project through slots 201 in 70

sideways 202 and connect the supports 200 to members 203 having friction rolls 204 rotatably mounted thereon. Brackets 205 are fixedly secured to or from part of the underside of table 5 10 and have a hole therein for the reception of rods 206 which are rigid extensions of members 203. At their free end rods 206 carry nuts 207 forming base plates for springs 208, brackets 205 forming the other abutting plates for said springs. 10 As clearly seen in Fig. 17, springs 208 constantly urge cutting tool mechanism 75 toward work support 20 and into operating position therewith. A cross member 210 is provided between extensions 15 203 and serves as an abutment designed to engage pawls 211 rigidly secured to the ends of a shaft 211a mounted between two brackets 212 fast to the frame of the machine, said pawls 211 being kept in engagement with member 210 by means of springs 213 connected at one end to said 20 pawls 211 and at its other to the underside of table 10. Rod 63a forming part of a foot treadle is connected to one of said pawls on its lower side and serves to move the pawl in a direction opposite to said springs 213 when the treadle is depressed. Levers 215 keyed to shaft 71a at their upper ends frictionally engage friction rolls 204 and lever 216 also keyed to shaft 71 at its lower end carries another friction roll or cam follower 217 engaging cam 61a rotatably mounted on main 25 30 drive shaft 42. Cutting tool mechanism 75 being continuously urged toward work support 20 by means of springs 208, depression of foot treadle withdraws pawls 211 and permits the cutting tool carriage 75 to slide in operating position with respect to work support 20. Cam 61a then performs one complete revolution and at its conclusion levers 215 have pushed the cutting tool carriage 75 out of operating position and away from work support 20 against the pull of spring 208. 35 40 45 50 55 60

40 Springs 213 then pull pawls 211 into place, providing a stop for carriage 75 until again released by the depression of treadle 62. Air cushions for cutting tool carriage 75 in its movement toward work support 20 are provided in members 202 and comprise hollow cylindrical chambers 220 having pistons 221 moving therein, rods 222 connecting said pistons with supports 200. Air is allowed to escape through an orifice 223, made adjustable by valve 224. In other respects the operation of this modification is the same as that shown in Figs. 1 to 15, and it will be seen that this modification merely reverses the movement between work support 20 and cutting tool carriage 75. This arrangement, however, permits easy adjustment of the machine to different size books, by quick replacement of an entirely new cutting tool carriage and mechanism 75, having a different inclination from left to right as shown in Fig. 16 and different toothed rack for controlling the step by step advance of the cutting tool carriage.

I claim:

1. In a book indexing machine of the class described, a frame, a work support for holding the book whose pages are to be notched, a cutting tool for cutting notches in the edge of the pages of said book, means for operating the cutting tool, means providing relative movement between the work support and the cutting tool to bring them into and out of operating position, and means providing a gradually extending movement of the cutting tool into and up the side of the book and at the same time a step by step advance of the cutting tool across the length of the book.

75 2. In a book indexing machine of the class de-

scribed, a frame, a work support for holding the book whose pages are to be notched, a cutting tool for cutting notches in the edge of the pages of said book, means for operating the cutting tool, means providing relative movement between the work support and the cutting tool to bring them into and out of operating position, and means providing a gradually extending movement of the cutting tool into and up the side of the book and means providing a step by step advance of the cutting tool across the length of the book.

3. In an indexing machine for cutting one or more rows of index notches along the opening side of a book, a frame, a work support for holding in open position a book whose pages are to be notched, having means for clamping and positioning the book with respect to a cutting tool, a cutting tool for punching notches in the edge of the pages of said book, means for operating the cutting tool, means providing relative movement between the work support and the cutting tool to bring them into and out of operating position, means including a row of gauge pins of varying length for providing a gradually extending movement of the cutting tool into and up the open side of the book in open position, and means including a toothed rack providing a step by step horizontal advance to the cutting tool across the length of the book.

4. In an indexing machine for cutting one or more rows of index notches along the opening side of a book, a frame, a work support for holding in open position a book whose pages are to be notched, having means for clamping and positioning the book with respect to a cutting tool, a cutting tool for punching notches in the edge of the pages of said book, means for operating the cutting tool, means providing relative movement between the work support and the cutting tool to bring them into and out of operating position, means including a row of gauge pins of varying length for providing a gradually extending movement of the cutting tool into and up the open side of the book in open position, and means including a toothed rack providing a step by step horizontal advance to the cutting tool across the length of the book.

5. In an indexing machine for cutting one or more rows of index notches along the opening side of a book, a frame, a work support for holding in open position a book whose pages are to be notched, having means for clamping and positioning the book with respect to a cutting tool, a cutting tool for punching notches in the edge of the pages of said book, means for operating the cutting tool, means constantly urging the work support toward the cutting tool, means for positively moving said work support away from the cutting tool, means including a row of gauge pins of varying length for providing a gradually extending movement of the cutting tool into and up the open side of the book in open position, and means including a toothed rack providing a step by step horizontal advance to the cutting tool across the length of the book.

6. In an indexing machine for cutting one or more rows of index notches along the opening side of a book, a frame, a work support for holding in open position a book whose pages are to be notched, having means for clamping and positioning the book with respect to a cutting tool, a cutting tool for punching notches in the edge of the pages of said book, means for operating the cutting tool, means for moving the work support to and from the cutting tool, means including a row of gauge pins of varying length for providing a gradually extending movement of the cutting tool into and up the open side of the book in open position, and means including a toothed rack providing a step by step horizontal advance to the cutting tool across the length of the book.

of the cutting tool into and up the open side of the book in open position, means including a toothed rack providing a step-by-step horizontal advance to the cutting tool across the length 5 of the book, and means constantly opposing said step-by-step horizontal advance of the cutting tool.

7. In an indexing machine for cutting one or 10 more rows of index notches along the opening side of a book, a frame, a work support for holding in open position a book whose pages are to be notched, having means for clamping and positioning the book with respect to a cutting tool, a cutting tool for punching notches in the 15 edge of the pages of said book, means for operating the cutting tool, means for moving the cutting tool to and from the work support, means including a row of gauge pins of varying length for providing a gradually extending movement 20 of the cutting tool into and up the open side of the book in open position, and means including a toothed rack providing a step-by-step horizontal advance to the cutting tool across the length of the book.

25 8. In an indexing machine for cutting one or more rows of index notches along the opening side of a book, a frame, a work support for holding in open position a book whose pages are to be notched, having edge gauges for clamping 30 and positioning the book with respect to a cutting tool, a cutting tool for cutting notches in the side of said book, means for operating the cutting tool, means for moving the work support to and from the cutting tool, one or more rows 35 of gauge pins of varying length for providing a gradually extending movement of the cutting tool into and up the open sides of the book in open position, said rows of gauge pins corresponding in number to the rows of index notches 40 to be placed on the book, means for bringing each row separately into position, and a toothed rack providing a step-by-step horizontal advance to the cutting tool across the length of the book.

45 9. In an indexing machine for cutting one or more rows of index notches along the opening side of a book, a frame, a work support for holding in open position a book whose pages are to be notched, having edge gauges for clamping 50 and positioning the book with respect to a cutting tool, a cutting tool for cutting notches in the side of said book, means for operating the cutting tool, means in said tool for carrying off the punched-out pieces, means for moving the work support to and from the cutting tool, one or more rows 55 of gauge pins of varying length for providing a gradually extending movement of the cutting tool into and up the open sides of the book in open position, said rows of gauge pins corresponding in number to the rows of index notches 60 to be placed on the book, means for bringing each row separately into position, and a toothed rack providing a step-by-step horizontal advance to the cutting tool across the length of the book.

65 10. An indexing machine for cutting one or more rows of index notches along the opening side of a book, comprising a frame, a work support for holding in open position the book whose 70 pages are to be notched, positioning and clamping means on said work support, a cutting tool for cutting notches in the edge of said book, means providing relative movement between the work support and the cutting tool to bring them into and out of operating position, means pro-

viding a step-by-step advance of the cutting tool across the length of the book, a main drive shaft having cams thereon for operating said cutting tool and said two last mentioned means, and a one-revolution clutch for bringing said machine 5 into operation.

11. An indexing machine for cutting one or more rows of index notches along the opening side of a book, comprising a frame, a work support for holding in open position the book whose 10 pages are to be notched, positioning and clamping means on said work support, a cutting tool for cutting notches in the edge of said book, means providing relative movement between the work support and the cutting tool to bring them 15 into and out of operating position, means providing a step-by-step advance of the cutting tool across the length of the book, a main drive shaft having cams thereon for operating said cutting tool and said two last mentioned means, means 20 providing a gradually extending movement of the cutting tool into and up the side of the book, and a one-revolution clutch for bringing said machine into operation.

25 12. An indexing machine for cutting one or more rows of index notches along the opening side of a book, comprising a frame, a work support for holding in open position the book whose 30 pages are to be notched, positioning and clamping means on said work support, a cutting tool for cutting notches in the edge of said book, means providing relative movement between the work support and the cutting tool to bring them 35 into and out of operating position, means including a toothed rack providing a step-by-step advance of the cutting tool across the length of the book, a main drive shaft having cams thereon for operating said cutting tool and said two last mentioned means, one or more rows of gauge 40 pins of varying length for providing a gradually extending movement of the cutting tool into and up the sides of the book in open position, and a one-revolution clutch for bringing said machine into operation.

45 13. An indexing machine for cutting one or more rows of index notches along the opening side of a book, comprising a frame, a work support for holding in open position the book whose 50 pages are to be notched, positioning and clamping means on said work support, a main drive shaft having a cam thereon for operating a cutting tool for cutting notches in the edge of said book, a second cam thereon operating means providing relative movement between the work support and the cutting tool to bring them into and 55 out of operating position, a third cam thereon operating means providing a step-by-step advance of the cutting tool across the length of the book, and a one-revolution clutch for bringing said mechanism into operation.

60 14. An indexing machine for cutting one or more rows of index notches along the opening side of a book, comprising a frame, a work support for holding in open position the book whose 65 pages are to be notched, positioning and clamping means on said work support, a main drive shaft having a cam thereon for operating a cutting tool for cutting notches in the edge of said book, a second cam thereon operating means providing relative movement between the work support and the cutting tool to bring them into and out of operating position, a third cam thereon operating means providing a step-by-step advance of the cutting tool across the length of the book, means providing a gradually extending 75

movement of the cutting tool into and up the side of the book, and a one-revolution clutch for bringing said mechanism into operation.

15. An indexing machine for cutting one or 5 more rows of index notches along the opening side of a book, comprising a frame, a work support for holding in open position the book whose pages are to be notched, positioning and clamping means on said work support, a main drive 10 shaft having a cam thereon for operating a cutting tool for cutting notches in the edge of said book, a second cam thereon operating means providing relative movement between the work

support and the cutting tool to bring them into and out of operating position, a third cam thereon operating means including a toothed rack providing a step-by-step advance of the cutting tool across the length of the book, means including one or more rows of gauge pins of varying length for providing a gradually extending movement of the cutting tool into and up the sloping sides of the book in open position, and a one-revolution clutch for bringing said machine into 10 operation.

5

HJALMAR ERICKSON.
